COMBINED TOY OIL WELL PUMP AND DERRICK

Kenneth B. Cope, Bradford, Pa.

Application May 5, 1955, Serial No. 35,820

Term of patent 14 years

(Cl. D34—15)

FIG. 1

FIG. 2

FIG. 3

Fig. 1 is a top plan view of a combined toy oil well pump and derrick, showing my new design;

Fig. 2 is a side elevational view thereof; and

Fig. 3 is an end elevational view thereof.

I claim:

The ornamental design for a combined toy oil well pump and derrick, as shown.
